R. H. MacINNES

HINGED OVEN BURNER

Filed July 27, 1923

INVENTOR

ROBERT H. MACINNES
BOSTON, MASS.
ATTY.

UNITED STATES PATENT OFFICE.

ROBERT H. MACINNES, OF HAMILTON, ONTARIO, CANADA, ASSIGNOR TO D. MOORE COMPANY, LIMITED, OF HAMILTON, ONTARIO, CANADA.

HINGED OVEN BURNER.

Application filed July 27, 1923. Serial No. 384,178.

To all whom it may concern:

Be it known that ROBERT H. MACINNES, a subject of the King of Great Britain, residing at Hamilton, in the county of Wentworth and Province of Ontario, Canada, has invented certain new and useful Improvements in Hinged Oven Burners, of which the following is a specification.

My invention relates to improvements in electric oven burners and consists essentially of a plurality of spaced parallel rails or guides, for fire bars or resistance insulating bars, integral with lateral metallic straps hinged to the oven floor structure and connected at their opposite ends by a cross member which is provided with means for fastening it to the oven structure, and lateral elevated strips on the said straps, and detachable therefrom, for the purpose of retaining said fire bars from lateral movement.

The principal object of the invention is to provide a suitably constructed heater element of the type carrying spaced rows of pluralities of fire bars, or resistance stringing bars or blocks held in position by spaced parallel rails or guides, which may be easily and readily swung to a substantially perpendicular position or a position intermediate of the latter and its normally horizontal position, for the purpose of clearing the oven floor beneath.

A further object is to provide means in a heater element of the class specified to keep the fire bars in proper relative position and which may be easily and readily detached so as to permit replacement of any of said fire bars.

A still further object is to provide such a device which will be simple, durable, efficient in operation, and inexpensive to manufacture.

These, together with other objects, may be attained by the construction, combination and arrangement of the parts as will be hereinafter more fully described, illustrated in the accompanying drawing, and pointed out in the claims hereunto appended.

Referring to the drawing:

50 Figure 1 is a top or plan view of the improved heater element;

Figure 2 is a side elevation of the same; and,

55 Figure 3 is a side elevation of the structure with the fire bars removed.

Similar reference characters refer to similar parts throughout the several views.

The type of heater element to which the present invention relates is that consisting of a plurality of fire bars 2 placed end to end and arranged in spaced parallel rows supported on horizontal rails or guideways 3 from which they may be removed and replaced by sliding off or on. Through suitably arranged holes in these fire bars are strung the resistance coils 4 in transverse relation to the rows thereof and longitudinally of the burner itself.

The transverse rails 3 are secured to lateral parallel metallic straps 5, preferably integral therewith as in this manner the rails and straps may be cast together, and the straps are connected at their forward ends by a cross member 6, also integral therewith. The rear ends of said straps are pivotally connected to bearing brackets 7 which are preferably permanently fixed to the oven structure A, and the forward cross-member 6 is provided with a slot 8 through which, when the heater element is normally positioned in contact with the oven structure, extends an eye 9 to receive a pin 10, for the purpose of retaining the heater element in normal. The eye is permanently secured to the oven structure A, and by disengaging the pin 10 from its eye the entire heater element may be swung clear of the oven structure, a suitable lip 11 being provided on the cross member 6 for manipulation.

To protect the ends of the fire bars 2 and to prevent them from displacement, there are provided longitudinal detachable strips 12. The said strips are elevated by forward and rear feet 13 and 14 respectively to a position preferably a perceptible distance above the tops of the rails 3 and spaced apart sufficiently to permit little or no lateral play among the fire bars 2. The feet 13 and 14 rest upon the straps 5, the rear feet 14 being bifurcated to embrace offset lugs or retaining pieces 5 formed on the said straps, and the forward feet 13 are provided with slots 16 through which extend eyes 17 also formed on the said straps and through which are placed pins 18. It will be observed that the said strips are immovable from the heater element as long as the pins 18 are placed, but by the removal of the pins the strips may be slightly raised at their forward ends and then by drawing 110

them forward the bifurcated feet 14 are withdrawn from their engagement with the lugs 15.

There has thus been provided a simple and efficient device of the character described and for the purpose specified.

Having now fully described my invention, what I claim and desire to secure by Letters Patent, is:

- 10 1. In a heater element of the class described including fire bars and resistances winding thereon, a pair of lateral parallel straps hinged to an oven structure and connected by a forward cross member, a plurality of spaced transverse rails for supporting the fire bars and connected to said straps, and means for securing the heater element to said oven structure at the end opposite to that which is hinged thereto.
- 20 2. In a heater element of the class described including fire bars and resistances winding thereon, a three sided frame hinged to an oven structure at the free ends of the frame, a plurality of spaced transverse rails for supporting the fire bars and connected to the sides of said frame whose ends are free, and means for securing the heater element to said oven structure at the end opposite to that which is hinged thereto.
- 30 3. In a heater element of the class described including fire bars and resistances winding thereon, a pair of lateral parallel straps hinged to an oven structure and connected by a plurality of spaced transverse rails for supporting the fire bars, and means for securing the heater element to said oven structure at the end opposite to that which is hinged thereto.
- 40 4. In a heater element of the class described including fire bars and resistances winding thereon, a pair of lateral parallel straps hinged to an oven structure, a forward cross member connecting said straps, a plurality of spaced transverse rails for supporting the fire bars and connected to said straps, and means on said forward cross member to secure the heater element to the oven structure at the end opposite to that which is hinged thereto.
5. In a heater element of the class described including fire bars and resistances winding thereon, a pair of lateral parallel straps hinged to an oven structure and connected by a forward cross member, and a plurality of spaced transverse rails for supporting the fire bars and connected to said straps.
6. In a heater element of the class described including fire bars and resistances winding thereon, a frame hinged to an oven structure, a plurality of spaced rails for supporting the fire bars and secured to said frame, and means for securing the heater element to said oven structure at the end opposite to that which is hinged thereto.
7. In a heater element of the class described including fire bars and resistances winding thereon, a pair of lateral parallel straps hinged to an oven structure and connected by a forward cross member, a plurality of spaced transverse rails for supporting the fire bars and connected to said straps and detachable means for holding said fire bars in place.
8. In a heater element of the class described including fire bars and resistances winding thereon, a pair of lateral parallel straps hinged to an oven structure and connected by a forward cross member, a plurality of spaced transverse rails for supporting the fire bars and connected to said straps, elevated detachable longitudinal strips running parallel with said strips and provided with feet to rest thereon, offset retaining lugs formed on one end of said strips, the feet on one end of said strips being bifurcated to embrace the necks of said lugs the heads of which span the intervening space between the bifurcations, and means for detachably securing the opposite ends of said strips to said straps and to effect engagement of the bifurcated feet with said lugs.

In testimony whereof I have affixed my signature.

ROBERT H. MACINNES.
